PERRY V. McCASH, OF SEATTLE, WASHINGTON

AUTOMATIC ELECTRIC-CURRENT-CONTROLLING MEANS

Application filed April 3, 1926. Serial No. 99,602.

This invention relates generically to means for intermittently turning on and turning off electric lights, such as are used in electric signs, street signals and at railroad crossings. Stated broadly, the invention comprises a plurality of load circuit switches, a control circuit switch, a plurality of electromagnets for controlling the opening and closing of the switches, and retarding means for retarding and delaying the action of the control-circuit switch.

Among the objects of this invention are to provide an improved mode of controlling the flow of current to a plurality of load circuits; to provide an improved structure for controlling the intermittent flow of electric current; to provide a structure in which the controlling electromagnets pull controlling armatures, substantially simultaneously, toward opposite ends thereof to control the functioning of the circuit; to provide a mechanism which will operate substantially uniformly, notwithstanding variations in the current strength of city lighting systems at different times of the day; and such further objects, advantages and capabilities as will hereafter more fully appear and as are inherent in the construction disclosed.

My invention further resides in the combination, construction and arrangement of parts illustrated in the accompanying drawings and, while I have shown therein one embodiment of my invention, I desire the same to be understood as illustrative only and not as limiting said invention.

In the drawings attached hereto and forming a part hereof, Fig. 1 is an elevation of a controlling switch in accordance with my invention; Fig. 2 is a diagrammatic view showing the wiring diagram of this new controlling switch. Fig. 3 is a top plan view of the device showing the relation of the walking beam, dash pots and a circuit breaker controlled by the walking beam; and Fig. 4 is a longitudinal section through an end of one of the armatures for one of the electromagnetic coils, showing the connection of one arm of the walking beam therewith.

Referring more in detail to the annexed drawings, numeral 1 designates the base or

panel upon which the parts of my construction are mounted, while numerals 2 and 3 denote a pair of electromagnets carried by the panel and having their terminals connected respectively to the terminals 2a, 2b, 3a and 3b. These electromagnets are provided with cores 4 and 5, said cores being preferably of laminated magnetic material.

A plurality of switch levers 6, 7, 6a and 7a are pivoted upon insulating posts 8 and 9 or 60 are insulated from these posts if they are not made of insulating material. These levers 6, 6a and 7, 7a are connected in pairs by the cross-bars 10 and 11 and each carries adjacent its extremity a contact 12, intermittently engageable with cooperating contacts 13, these contacts being designated specifically by the numerals 12a, 12b, 12c, 12d, 13a, 13b, 13c and 13d. It will be seen by referring to Fig. 2 that the two forward contacts 13 are carried by L-shaped conducting bars 14 and 15 which are integral with or secured to members 16 and 17 whereby they are mounted upon the panel 1. Also, the rearward contacts 13 are mounted in horizontal extensions from the mounting pieces 18 and 19, shown most clearly in Fig. 1. A pair of connecting posts 20 and 21 are mounted upon the panel 1 and have flexible conductors 22, 23, 24 and 25 leading therefrom to the levers 6a, 7a, 6 and 7, respectively. From this it will be apparent that the conductors 22 and 23 go to the rearward pair of contact levers, while the conductors 24 and 25 go to the forward levers. From the cross-bars 10 and 11, which are insulated from the contact levers, there extend upwardly paramagnetic means 26 serving as armatures for the cores of the electromagnets. These means 26 pass through openings in the angular diamagnetic members 27 and are capable of reciprocating therein toward and away from cores of the coils.

Above the electromagnet is a walking beam 28 pivoted upon a post 29 and having an arm 30 extending upwardly therefrom. The extremities 31 of this walking beam are reduced and pass through suitable apertures 32 in the armatures 33 (which, it will be understood, are paramagnetic) of the electro-

magnets 2 and 3, being insulated therefrom in any suitable manner. The armatures 33 are provided at their upper ends with piston heads 33a which have a close sliding fit in the cylinders 34 which serve as dash pots for controlling the rate of oscillation of the walking beam 28. Means such as screws 35 is provided for regulating the rate at which air may escape from the dashpots, thus making it possible to adjust the speed of operation of this device. Suitable insulating means 36 at the upper end of arm 30 insulate this walking beam from the switch member 37, as will be readily understood. The supporting means 38 and the contact 39 are carried by a bracket 40 which also carries a spring contact member 41, which latter is in electrical contact with the contact member 37. A lead 42 extends from the contact member 39 to the connecting post 43 which is connected electrically with the connector 44 for the neutral load wire of a three wire system. The functions of the connectors 45, 46, 44a, 45a, 46a, 47, 48 and 49 will be presently described.

Referring now to Fig. 2, numeral 50 designates a source of current from which lead the conductors 51, 52 and 53. These conductors are connected respectively to the connectors 47, 48 and 49 for furnishing the current to be controlled, said current passing through my new control switch described above. After passing through this control switch, the current is distributed to the load wires 54, 55, 56, 54a, 55a and 56a as will be readily understood, these load conductors being connected respectively to the connectors 45, 44, 46, 45a, 44a and 46a.

Assuming the switch contacts 37 and 39 to be in engagement and that all of the switches 6, 7, 6a, 7a are closed, when the current is turned on, it will take the following course:

From source 50 through wires 51, 52 and 53 to the connectors 47, 48 and 49. Since the current flowing through switches 6, 6a and 7 does not enter into the control of the circuit but is merely fed through those switches to the contacts to which the load circuit is connected, the circuit through these three switches will, for the present, be disregarded. The current flowing through connector 49 passes through conductor 60 to post 20 and from thence through conductor 23, switch lever 7a, contacts 12d, 13d and bracket 19, where it divides, part flowing through conductor 61 to connector 46a, from which it is fed to the load circuit, and part passing through control conductor 62 to connector 2b, coil 2, connector 2a and back through conductor 63, connector 48 and conductor 52 to the source 50. While, under the circumstances indicated, the circuit is now closed through connector 44 and load conductors 54, 55 and 56 as well as through contacts 37 and 39, and both coils 2 and 3, the circuit will not

remain closed as indicated when the current is turned on, for the following reason:

Since the current which flows through switch 7a, conductor 62 and coil 2 is under control of electromagnet 3, the flow of this current through the indicated switch and the coil 2 will cease immediately upon the circuit being closed, because current flows from connector 49 through conductor 65, connector 3b, coil 3, connector 3a, switch contacts 37, 39 and return conductor 63. The flow of current through this circuit is not immediately interrupted, since the same is not under the influence of an immediately responsive electromagnetic switch. The current will therefore continue to flow through electromagnet 3 until the attraction thereof for the armature 33 has caused this and the piston carried thereby to move downwardly far enough to cause separation of the contacts 37 and 39 by the rocking of the walking beam 28. As soon as these contacts are separated, current ceases to flow through coil 3 and contact levers 7 and 7a drop so that the circuits through contacts 12c, 13c, 12d and 13d are closed and current flows to connectors 45a, and 46a and from there to the load circuit. Also, current now flows through switch 12d, 13d, conductor 62 and coil 2. This results in the switch levers 6 and 6a being pulled toward the electromagnet 2 and the circuits to connectors 45 and 46 being broken. Current will now flow through the circuits as follows:

From 49 through 60, 20, 23, 7a, 12d, 13d, 19, 61, 46a, load, 44a, 44, 63 and 52. Current also flows from 19 through 62, 2b, 2 and 2a, returning through 63 and 52 as above. Current also flows through 51, 47, 21, 25, 7, 12c, 13c, 15, 67, 45a, load, 44a, 44, 63 and 52. As soon as the current starts to flow through coil 2, it causes the pulling of armature 26, attached to switch levers 6 and 6a, toward the electromagnet and also the pulling of armature 33 toward the core 4. The piston in cylinder 34 will retard the action of this bar and the closing of the switch contacts 37 and 39, but as soon as these contacts are closed, coil 3 is again energized with the result that the circuit through 12d and 13d is again broken and coil 2 de-energized. This causes the armature 33 to again swing downwardly on the right toward electromagnet 3 as indicated above, thus resulting in a repetition of the action outlined above. The speed at which these changes are made can be varied by proper adjustment of the adjusting means 35, as set forth above. It is thought that further explanation of how the current flows through the electromagnetic switches and the conductors 61, 67, 68 and 69 to the terminals 45, 46, 45a and 46a will now be unnecessary.

It is believed it will now be apparent from the present disclosure that the structure herein set forth is adapted to accomplish the various objects recited.

Having now disclosed my invention.

I claim:—

1. In a light circuit controlling device, a lever having a plurality of arms, said lever being pivoted substantially centrally, dash-pots arranged on opposite sides of the pivot of the lever and substantially symmetrically with relation to the pivot and arms of the lever, pistons in the dash-pots, means connecting the pistons and the adjacent arms of the lever, electromagnet coils external to the dash-pots, each having an end adjacent said connecting means and serving to attract the same toward the coils when the coils are energized, and switches at the opposite ends of the coils, said switches being magnetically attracted toward the coils axially substantially simultaneously with said connecting means.
2. A structure as defined by claim 1 having a switch connected to the lever to be opened and closed thereby upon oscillation thereof.
3. A structure as defined by claim 1 having a switch connected to the lever to be opened and closed thereby upon oscillation thereof, said switch controlling the circuit through one of the electro-magnets.
4. In a light circuit controlling device, a lever having a plurality of arms, said lever being pivoted substantially centrally, guiding means arranged substantially symmetrically with relation to the pivot and arms of the lever, paramagnetic means slidable in the guiding means, means connecting the paramagnetic means and the adjacent arms of the lever, electro-magnetic coils external to the guiding means and capable, when energized, of attracting the paramagnetic means, and switches at the ends of the coils opposite the paramagnetic means, said switches being magnetically attracted toward the coils axially thereof substantially simultaneously with the paramagnetic means.

45 In witness whereof, I hereunto subscribe my name to this specification.
